UNITED STATES PATENT OFFICE.

SAMUEL J. WEBB, OF MINDEN, LOUISIANA.

MOTOR.

1,015,411.

Specification of Letters Patent.

Patented Jan. 23, 1912.

Application filed November 14, 1907. Serial No. 402,168.

To all whom it may concern:

Be it known that I, SAMUEL J. WEBB, a citizen of the United States, residing at Minden, in the parish of Webster and State 5 of Louisiana, have invented certain new and useful Improvements in Motors, of which the following is a specification.

My invention relates to motors and especially to that class of motors in which the 10 power is derived from the use of gases or a gaseous mixture under pressure, and my invention consists in means whereby to rapidly and continuously produce such an admixture by the combustion of a mixture 15 of air compressed by the action of the motor, and a vaporized or gaseous fuel, as set forth hereinafter, and illustrated in the accompanying drawing, in which—

Figure 1 is an elevation in part section 20 showing my apparatus in connection with a motor and a compressor which may be of the rotary type and of any suitable construction; Fig. 2 is an end view; and Fig. 3 an enlarged sectional view of the mixer.

25 The compressor A and motor B may be of any suitable character, but as indicated each is rotary, and the shaft of the motor is extended to operate the compressor which has inlets at α through which the air enters 30 and a discharge pipe 9 provided with a suitable check valve 10 and leading to an air tank or receptacle E. With the motor is connected a supply pipe 12 through which the motor fluid passes.

35 In the construction illustrated in the drawing, the fluid supplied to the motor consists of the expanded gases resulting from the combustion of an admixture of air and liquid fuel or gas, and the expanded 40 gases or motor fluid thus produced are secured by introducing a mixture of air and fuel through a pipe 3 into the combustion chamber y of a casing C, which communicates with the pipe 12, the air being carried 45 under pressure from the compressor A or the reservoir E in which it is stored through a pipe 2 provided with a check valve 14 and with a suitable control valve 9.

The proper admixture of air and liquid 50 fuel is effected in a mixer D. This mixer has a casing 16 communicating with the pipes 2 and 3 between which is a port 17 closed by a valve 5 and a channel 18 communicating with the pipe 7 is closed by a 55 valve 6, the channel 18 and the port 17 being of different sizes and the valves 5 and

6 being so proportioned, and both being carried to move together, that when they are raised to open the port and channel, there will be the proper proportion of air to liquid fuel passing through said ports and to the pipe 3. In order that the valves 5 and 6 may move together they are carried by the same screw stem 4 which may be turned by means of a handle 19, but to vary the proportions in consequence of difference in the character of oils used the valve 6 is carried by a screw stem 20 adjustable in the stem 4. The pipe 7 communicates with an oil reservoir H that is provided with a check valve 21 and control valve 8, and the reservoir H communicates with the reservoir E through a pipe 23 provided with a control valve 24. By this means there is a constant pressure upon the oil tending to carry it forcibly to 75 the mixer, and there is a constant pressure upon the air tending to force it through the mixer, and when the control valves are properly adjusted the air and the oil will be carried to and through the pipe 3, and 80 the oil will be dispersed or sprayed or atomized forming with the air a combustible mixture which passes to the combustion chamber y .

In the combustion chamber the mixture 85 may be ignited in any suitable manner, as by means of an electrical igniter 26, and so long as the mixture is supplied and the heated gases withdrawn there will be a continuous combustion and the formation 90 of a motor fluid under pressure, which passes to the pipe 12 and operates the motor B.

In order to maintain the combustion within the receptacle C I provide a refractory body or material 29 which will become 95 highly heated by the burning mixture, and in case of temporary cessation of the flow to or from the chamber will serve to ignite the fresh mixture as soon as introduced.

The air which is compressed in and forced 100 from the compressor A will be stored to a certain extent in the receptacle E and prevented from flowing back by the check valve 10 so that the motor may be started by means of the air thus held under pressure in the receptacle E. In order that the motor may be started before any mixture is introduced and ignited, I make use of the tank or receptacle F which communicates with the pipe 12 through a pipe provided 105 with a check valve closing against the pressure in the tank F, but capable of being

raised by means of a lifter 30 of suitable character. When thus raised the gases which have been stored under pressure in the receptacle F may pass to and operate 5 the motor B, and this in turn serves to start the compressor A and furnish the supply required for further operation. The receptacle C may be provided with a safety valve J and with a pet cock K, and preferably the safety valve is so adjusted that the pressure in the combustion chamber y will always be maintained lower than that of the air discharged from the compressor or in the tank E, and so as to insure a flow of 10 air from the mixer into the chamber and control the same automatically.

It will be seen that by the arrangement above described I am enabled to afford a constant supply of motor gases under pressure 20 to the motor and to maintain the compressor in operation, and that the compressed air thus obtained is effectually employed to furnish the necessary amount of air to the mixture of air and liquid fuel, and 25 also to vaporize or atomize the latter, but it will of course be understood that in some cases I may use gas instead of liquid fuel, or may vaporize the liquid fuel before combining it with the air. The motor thus put 30 in operation by the continuous generation of gases as above described is suitably geared as by means of a pinion 30 with any part which has to be driven thereby.

It will of course be understood that the 35 motor gases from the apparatus C may be used for operating a plurality of motors together or independently, for which purpose one or more branch pipes 31 provided with control valves 32 may be used. The flow to 40 the engine may be controlled by a throttle. While the air may flow freely to the compressor at all times, I prefer to cut it off automatically whenever the pressure tends to exceed that which is required. For 45 this purpose I control the air inlet pipe 33 leading to the inlet at x by means of a gov-

ernor valve 34 controlled by an ordinary pressure regulator 35, which is supplied with air under pressure by a pipe 36 communicating with the receptacle E.

Without limiting myself to the precise construction and arrangement of parts shown, I claim as my invention—

1. An apparatus of the class described comprising a source of compressed air, 55 means for maintaining the pressure of the air below a predetermined amount, a working fluid generating chamber, a fuel supply chamber, a mixer, means connecting the source of compressed air with said mixer, means connecting the fuel chamber with said mixer, means connecting the source of compressed air with said fuel chamber, means connecting said mixer with said generating chamber, and a safety valve on said generating chamber and adapted to maintain the pressure in said generating chamber below the pressure in said source of compressed air.

2. An apparatus of the class described 70 comprising a source of compressed air, means for maintaining the pressure of the air below a predetermined amount, a working fluid generating chamber, a fuel supply chamber, a mixer connected with said generating chamber, means connecting the source of compressed air with said mixer, means connecting the fuel chamber with said mixer, said mixer having means for simultaneously varying the supply of air and fuel in fixed 75 proportions, means connecting the source of compressed air with said fuel chamber, and a safety valve on said generating chamber adapted to maintain the pressure in said generating chamber below the pressure in said source of compressed air.

In testimony whereof I affix my signature in presence of two witnesses.

SAMUEL J. WEBB.
